tigraph Corporation, Cleveland, Ohio, a cor-
poration of Delaware

Application January 14, 1933, Serial No. 651,686

9 Claims. (Cl. 101—58)

This invention relates to printing machines and more especially to a selector mechanism for printing machines of the character used to make impressions from a series of individual printing devices which are sequentially progressed through the machine.

In the past, printing machines of the type mentioned have been constructed to print with the selected printing devices and skip all other devices. The selection of the printing devices has been made in various manners, one of which is illustrated in my copending application, Serial No. 503,160, filed December 17, 1930. Such selectors are usually controlled by suitable indicia carried by printing devices, such as by removable tabs, notches, openings or the like.

The general object of the present invention is to provide an efficient arrangement to enable the printing mechanism to print with selected printing devices and skip the non-selected printing device, or to skip selected printing devices and print with the non-selected printing devices, as desired.

A further object is to provide a selector control mechanism which may readily be associated with various types of printing machines already in use, as well as incorporated in newly constructed machines.

A still further object is to provide a selector mechanism which will coact mechanically with the tabs or other indicia carried by the printing devices, but which mechanism will control the operation of the printing machine through an electrically operated mechanism, which may be readily controlled by the operator to print or to skip selected printing devices as desired.

Other objects of this invention will become more apparent from the following description, which refers to a preferred embodiment of the invention as illustrated in the accompanying drawings.

In the drawings, Figs. 1 and 2 are vertical longitudinally extending sections through a printing machine embodying my invention, as indicated by the correspondingly numbered lines on Fig. 3; Fig. 3 is a horizontal section as indicated by the lines 3—3 on Fig. 1; Fig. 4 is a transverse vertical section as indicated by the lines 4—4 on Fig. 3; Fig. 5 is a plan view of one form of printing devices which may be employed in the machine; Figs. 6 and 7 are perspective views of tabs which may be removably positioned on the printing devices; Figs. 8 to 10 inclusive are fragmentary views, in substantially the same plane as Fig. 1, but on an enlarged

scale, and illustrate various positions of the mechanism; Figs. 11 to 15, inclusive, are electrical diagrams illustrating the various electrical circuits to accomplish the selection, or to stop the machine, as desired.

In the accompanying drawings, I have illustrated my invention as embodied in a printing machine, which may, for example, be of the character disclosed in my Patent No. 1,930,798, issued October 17, 1933, Serial No. 503,160, filed December 18, 1930. Such machine includes a frame 10, which supports a printing device magazine M, a printing platen P, together with suitable mechanism to feed printing devices D across the table of the machine from the magazine to an anvil 40 located below the platen.

In the mechanism illustrated in the drawings, the printing devices are stacked in the magazine M by the operator and are successively withdrawn therefrom and passed along a guideway 20 by pawls 21 suitably mounted on feed bars 22. The feed bars 22 are carried by flanged rollers 23, which are rotatable on studs carried by the side walls of the guideway.

The feed bars are reciprocated from a drive 25 rocker 24 which is rotatably journaled on a shaft 25 carried by the main frame 10, and is oscillated in any well-known manner. Pivottally connected to the slide bars 22 by a link 30 is a bell crank 31, which is mounted on a stud 32 carried by the frame 10. The bell crank 31 is connected by a link 33 to a rock arm 34, pivotally mounted on a shaft 35 carried by the frame 10. The rock arm 34 is connected by a link 36 to the driving arm 24, heretofore mentioned. This arrangement is such that, when the driving arm 24 swings in a clockwise direction the feed bars will be drawn rearwardly (toward the left in Fig. 2), and when the rock arm 24 is swung in a counter-clockwise direction the feed bars will be drawn forwardly (toward the right). During the latter or forward movement of the feed bars, the pawls 21 engage the plates and advance them step by step from the magazine to a position above an anvil 40, in which position the printing device D is shown.

The platen P is of the oscillatory type and is mounted so as to strike the printing devices, while they are at rest on the anvil 40. As shown in Fig. 2, the platen is carried on the outermost end of a platen arm 41, which is pivotally mounted on the shaft 35 heretofore described. The lower end of the platen arm 41 is provided with a roller 43 arranged to coact with a cam slot 44 in a lever 45 pivotally mounted on the shaft 25.

The oscillating movement of the driving arm 24 is imparted to the platen driving arm 45 through the medium of a latch 47, which is operated by a selector mechanism hereinafter more fully described. Consequent upon the clockwise movement of the driving arm 24, the movement of the arm 45 and its cam 44 swings the platen in a clockwise direction toward the anvil 40 and an impression is made from the printing device 10 through a suitable inking ribbon, not shown.

As shown in the drawings, the selector mechanism includes a detector carriage 50, arranged to operate upon the printing devices when they are in the position of the device D2 of Fig. 2, 15 which position is immediately preceding the printing position indicated by the device D1. As shown in the drawings, the detector is in the nature of a bail overhanging the guideway 21 and pivoted to a shaft 52 carried by the frame. The 20 arrangement is such that the detector carriage 50 projects over selector tabs T which are carried on the far end of the printing devices, as shown in Fig. 5.

The detector carriage 50 includes a plate 53 25 provided with a series of openings 54, there being shown four openings arranged above each possible position of the tabs, which are removably positioned in notches 17 of the printing devices. Pins 55 may be selectively inserted in the 30 openings 54 and retained in place therein by a cover plate, the pins depending below the lowermost surface of the carriage. The detector unit 50, the carriage together with the pins 55 are urged downwardly as a unit by a compression 35 spring 60, which is interposed between the carriage 50 and a rock arm 56, and is engaged once in each cycle of operation by a pawl 57 pivotally carried by the rock arm 34, heretofore mentioned.

40 The selection is made by oscillating the carriage 50, causing it to move downward. If, on this downward movement, one of the pins 55 strike an abutment on the tab, further downward movement of the carriage is prevented and the 45 selector mechanism operates to position the latch 47 to produce the desired effect as to the printing or skipping of the selected printing device.

The latch mechanism 47 controls the operation of the platen, but has no effect upon the 50 plate feed members 22. This latch comprises a latch member 70, pivoted at 71 to the driving arm 24, and normally retained in an uppermost or normal position, the end 75 thereof engages a block 76 carried by the cam arm 45.

55 When the driving arm 24 is returned or moved in a counter-clockwise direction, it carries with it the cam arm 45. To this end, a block 76 is secured to the forward (right hand) face of the arm 45 and extends beyond its farthest face into 60 a slotted opening 81 in the arm 24 a distance sufficient to be engaged by the end surface of the slot 81 in the arm 24. Hence, when the arm 24 moves in a counter-clockwise direction the cam arm 45 will be positively drawn in a counter-clockwise direction by the driving arm 24.

The latch member 70 of the cam arm clutch 47 is operated by a roller 90 carried by a lever arm 92. When the arm 92 is swung in a clockwise direction it acts to cam the latch member 70 downward, causing it to disengage the abutment 76, thereby breaking the driving connection between the members 24 and 45.

75 The arm 92, which controls the operation of the latch 47 and the driving connection between the arms 24 and 45, is controlled by a solenoid

110 mounted on the frame 10. As shown in Figs. 1 and 2, the arm 92 is rigidly secured to a transverse shaft 101, which is rotatably mounted in the frame 10. Rigidly secured to this shaft is a bell crank 114, one end of which is drawn into engagement with a roller 115 carried by a bell crank 116, hereinafter to be described more fully. To maintain contact between the arm 114 and the roller 115, the other arm of the bell crank 114 is connected by a spring 117 to the frame 10. In 10 the position of the parts shown in Fig. 1, the roller 115 rests on the upper surface 120 of an arm 121, pivoted at 122 to the frame 10, and normally swung in a clockwise direction by a suitable tension spring 123. The movement of the 15 arm 121 is limited by suitable stops 124.

During the time when the selection of the printing device is made by the detector 50, the bell crank 116, which is pivoted to the frame 10 at 20 125, is struck by a pawl 130 carried by the rock arm 34, heretofore mentioned, and the bell crank 116 is swung in a counter-clockwise direction. As the bell crank swings, it raises the roller 115 out of contact with the arm 121, permitting the 25 spring 123 to swing the arm 121 in a clockwise direction to contact with the left hand pin 124 (Fig. 1). If, at this time, the detector member has been positioned so as to energize a solenoid 110, as hereinafter more fully described, a plunger 131 of the solenoid will strike an arm 132 of the 30 member 121, causing it to swing in a counter-clockwise direction, and, as the pawl 130 passes over the shoulder 133 of the lever 116, the lever will be drawn downwardly through the action of the spring 117 and the bell crank 114. This will 35 cause the roller to rest upon the surface 120 of the member 121, in which position the lever 92 will remain as shown in Fig. 2, and the latch mechanism will operate to maintain the driving connection between the driving member 24 and the cam 40 arm 45.

If, at the time the bell crank 116 is swung clear of the member 121, the detector member 50 should be so positioned that it would not cause an energization of the solenoid 110, the spring 123 would 45 maintain the member 121 swung in an extreme clockwise direction, in which instance an upwardly extending projection 136 of the member 121 would lie beneath the path of the roller 115, and when the pawl 130 disengaged the shoulder 50 143 of the lever 106 the compression spring 123 would maintain the member 121 in its extreme clockwise position and the roller 115 would rest on the upper surface of the projection 136, causing the bell crank 114 to be maintained in its extreme 55 clockwise position. This will cause the arm 92 to be in such position that, upon return movement of the driving arm 24, the roller 90 of the arm 92 would strike the raised surface 137 of its latch member 70, causing the driving connection of the latch 47, between the driving member 24 and the cam arm 45, to be broken. This, of course, would have no effect upon the plate feed mechanism, which would continue to function 60 as long as the driving arm 24 was operating. 65

There are two positions in which the detector 50 may be stopped. Its downward movement may be stopped by contact of one of the pins 55 with the surface T1 of the tab, or by contact with the tab between a pin and a raised surface T2 of the 70 tab. I have so arranged my mechanism that these positions of the detector 50 operate certain electric switch members to operate the solenoid 110 so as to print a selected plate and skip all other plates, or to skip the selected plate and print 75

the remaining plates, according to the setting of a manual switch 300.

Assuming the machine is set to print the selected plates, that is, the plates having tabs having raised surfaces T2 positioned beneath a selector pin 55, and to skip or fail to print all other printing devices. Under such conditions the various positions of the parts is as illustrated in Figs. 1, 2, 8 to 10, inclusive, and the electrical diagrams 11 to 13, inclusive. In these figures the normal position of the parts is shown in Figs. 1, 2, 8 and the diagrammatic Figure 11. It will be noted that in this position the detector member 50 is swung counter-clockwise to its extreme position and is maintained in such position by the spring 50a, Fig. 3. The parts remain in this position while the plate feed is operating to feed the printing devices on their step-by-step movement. Then, after the platen starts on its downward stroke and while the plate feed is returning without disturbing the position of the printing devices, which remain at rest in the guideway 20, the arm 34 acts through the pawls 57 and 130 to swing the detector driving lever 56 and the resetting bell crank 116, respectively. The movement of the arm 56 is imparted to the detector 50 through the medium of the compression spring 60. Hence, the detector may stop before the arms 34 and 56 have completed their full stroke, without damage to any of the operating mechanism.

Assuming now, that the printing device which is in the detecting position, is provided with a tab which does not have a raised portion T2 in a position to coat with any of the pins carried by the detector, the operation is as follows: As the arm 34 moves in its clockwise direction, the detector 50 and the driving arm 56 are swung from the position shown in Fig. 8 to the position shown in Fig. 10, causing an operating pin 200 and 210 (which are carried by a depending arm on the detector member 50) as well as the pin 220, which is carried by the lever 56, to swing into position to strike respective switch members 201, 211 and 221, which are carried by a frame bracket 151, changing the switches from the position shown in Fig. 1 to the position shown in Fig. 13, opening the normally closed switch 212 and closing the normally open switch 202 and 222.

The switch 202 is interposed between the source 50 of power, such as the battery 240, and the switches 212 and 222, which are selectively coupled to the solenoid 110, as will hereinafter be described. It follows, therefore, that as the switch 202 is closed, the battery will be connected with the switches 212 and 222. However, the manually-settable switch 300 has previously been positioned to connect the switch 212 with the solenoid 110 and at the same time to disconnect the switch 222 from such solenoid. Hence, the energization of the switch 222 will have no effect upon the solenoid 110. Therefore, as the pawl 130 slips past the timing lever 116, that lever will be swung in a clockwise direction by the spring 117, heretofore described, and the roller 115, carried by the lever 116, will rest on the upper edge of the projection 136, which was swung into position in the path of the roller by the spring 123, as the timing lever 116 was swung by the pawl 130. This position of the roller 115 causes the bell crank 114 and the arm 92 to be swung in a clockwise direction. The roller 90 will therefore, on the next clockwise movement of the driving arm 24, swing the latch member 70 into a position where it will not contact with 75 its abutment 76, and the driving connection be-

tween the driving arms 24 and 45 will be broken, with the result that the platen will not move on the next cycle of operation.

Notwithstanding the above operation, the plate-feeding device will continue to function, as its driving connection with the driving arm 24 remains active, being unaffected by the solenoid 110. Therefore, though the plate D progresses to the printing position on the return stroke of the parts, such plate will not be printed from. Similarly, all of the printing devices, which have no tabs having raised portions in positions corresponding to a pin in the detector 50 will be skipped or passed through the machine without having any impression made therefrom.

When a printing device, carrying a tab having a raised portion which projects into the path of one of the detector pins lies in the detecting position, the mechanism will print by that plate on the next cycle of operation,—assuming, of course, that the operator has not moved the manually operable switch 300. Under the conditions above described, the detector will be stopped in the position shown in Fig. 9, and the electric circuit will be as shown in the diagrammatic Figure 12. The detector arm will be stopped short of its full stroke by the tab. Likewise, the switch operating pins 210 and 220 will be carried a shorter distance than they were when the tabs did not present raised portions to the detector pins, as heretofore described. However, the timing pin 200 will be positioned the same as if no tabs were present, as this pin is carried by the member 56 which moves its complete stroke, regardless of the stopping of the detector unit 50.

When a plain tab is present, as above described, it will be noted from Fig. 12 that the switches 212 and 222 are open, and the switch 202 is closed. As the switch 202 closes the circuit between the battery and the switch 212 will be completed. The manually operable switch 300 being unchanged from the position heretofore described, the switch 212 now completes the circuit to the solenoid 110, causing the latter to be energized. The energization of the solenoid 110 causes its plunger 131 to rock the lever 121 against the action of the spring 123, permitting the roller 115 of the timing lever 116 to be drawn, under the action of the spring 117, onto the upper surface 120 of the lever 121, when the pawl 130 slides past the block 133 of the timing lever. The upwardly extending projection 136 of the lever 121 serves to prevent the return of the lever 121 after the current has been cut off from the solenoid, due to the opening of the timing switch 300 on the return movement of the member 34. In this position the arm 92 will be swung in its counter-clockwise direction, and will, on the next cycle of operation, remain in such position, causing the clutch 41 to remain active. The driving connection between the arm 24 and the platen driving arm 45 will therefore remain intact and the platen will operate to make an impression from the address plate when it arrives at the position beneath the platen, on the next cycle of operation on the mechanism.

The operation so far described has been confined to that setting of the machine in which the apparatus functions to print selected plates and to skip all non-selected plates. However, as heretofore mentioned, I have so arranged my apparatus that the operator may readily adapt it to print the non-selected plates and skip the selected plates, merely by throwing the manual switch 300.

The circuits of the operation just referred to are illustrated in the diagrams of Figs. 14 and 15. When the operator desires to skip the selected plate, the switch 300 is moved from contact with the switch 212 into contact with the switch 222, making the circuit from the solenoid 110 pass through the switch 222, rather than through the switch 212, as heretofore described. Therefore, the switch 212 will not be considered in connection with the operation of the mechanism with this position of the switch 300.

Under the above conditions, when the detector 50 descends, the pins thereof failing to strike a raised portion of a tab, the position of the detector 15 unit is the same as heretofore described in connection with Fig. 10. The switch operating pins will be moved to the same relative position as they were when the switch member 300 was contacting with the switch 212. However, the switch 20 222 will have been closed and the circuit is therefore made through the timing switch 202, the switch 222 and the manually operable switch 300, to the solenoid 110, energizing such solenoid. This causes the arm 121 to be swung in a counter-clockwise direction, which results in maintaining the driving connection between the arm 24 and the arm 45, and the platen will therefore operate to make an impression from the printing device 25 on the next succeeding cycle of operation.

Assuming that the switch 300 still remains in contact with the switch 222, and a printing device having a raised portion of a tab thereon is positioned beneath the path of the detector 50, the detector member will be stopped short of its full 30 stroke, and the position of the switches will be as illustrated in Fig. 15. In this position it will be noted that the switch member 222 has not been closed. Therefore, the circuit between the closed timing switch 202, the manual switch member 300 35 and the solenoid 110 is broken at the open switch 222 and the solenoid will not operate. The driving connection between the driving arm 24 and the driving arm 45 is therefore broken, causing the platen to fail to function on the next cycle of 40 operation but permitting the printing device feed to function as usual.

From the foregoing description, it is readily apparent that I have provided a selector device which may be used in conjunction with a printing 50 machine, together with a plurality of individual printing devices having indicia selectively positioned thereon, such as tabs, which selector may be readily controlled by the operator of the machine, so as to cause the apparatus to function to 55 print the selected units and skip the non-selected units, or to print non-selected units and skip selected units.

I claim:

1. In an address printing machine, the combination of means for feeding address plates having indexes carried thereby to a printing position, means including electric switches and circuits and mechanisms controlled thereby to cooperate with the indexes to control the printing mechanism, 60 and a manually operable electric switch to determine whether the machine prints or skips a plate, having indexes cooperating with said means.

2. In a machine of the character described, the combination with means for feeding serially to 65 printing position a set of address plates, some of which have index tabs carried thereby, of mechanism adapted to move across the position normally occupied by said tabs, a series of electric contacts actuated according to whether the said 70 mechanism engages or misses a predetermined tab,

platens operating mechanism controlled by said contacts, and an electric switch for determining whether the platen will be operated when said mechanism engages a tab or when it misses predetermined tabs.

3. In a machine of the character described, the combination of mechanism for feeding address plates serially to printing position, a platen adapted to coact with such plates, platen operating means, mechanism including a solenoid operatively connected to the platen operating means to connect or disconnect said means from said platen, a plurality of electrical circuits, controlled by indexes on the plates, one of said circuits being operative on said solenoid to cause the platen to print 15 plates having predetermined indexes and skip other plates, the other of said circuits being operative on said solenoid to cause the platen to print all plates not having said predetermined indexes and skip all plates having said predetermined indexes, and a manually operable switch to select the circuit to operate on said solenoid.

4. In a machine of the character described, adapted to print from a plurality of address printing plates, some of which have predetermined indexes thereon, the combination of a mechanism for feeding said plates serially to printing position, a platen adapted to coact with said plates, operating means for said platen, a clutch to connect said operating means with said platen, operating 30 means for said clutch including magnetic means, an electric circuit connected with said magnetic means, a pair of electric switches, means responsive from said indexes to operate said switches, and a manually operable means to selectively connect one of said switches with the magnetic means, a source of electrical energy, and a timing switch interposed between said source and said pair of switches.

5. In a machine of the character described, the combination of mechanism for feeding address plates serially to printing position, a platen adapted to coact with such plates, driving means for said platen, mechanism controlled by indexes on the plate next preceding the plate in 45 printing position for determining whether such plate shall be printed from, said mechanism including a solenoid and an electrical circuit, a pair of electrical switches both operative simultaneously by said mechanism whenever said mechanism cooperates with an index, a connection arranged to be operated on by said solenoid to disconnect the driving connection between the platen and its driving means on the next printing stroke of the platen, and settable means to 50 determine which of said switches will be operable on said circuit.

6. In an address printing machine of the type arranged to print addresses from a series of address plates, a platen, means to feed the plates 60 one at a time to printing position, means to operate the plate feed and the platen, a clutch connection between said operating means and the platen, selector mechanism responsive to indexes carried by the address plates to control the operation of said clutch, said selector mechanism including a normally open electric timing switch, a pair of electric selector circuits responsive to said indexes, an electrical connection between the timing switch and said selector circuits, magnetic means connected to operate said clutch, a manually settable means to selectively connect the magnetic means with one of said selector circuits, and means operative on said timing switch to connect the selector switches with a source of 70 75

electrical energy once in each cycle of operation of the machine.

7. In an address printing machine of the type arranged to print addresses from a series of address plates, some of which have predetermined indexes thereon, a platen, means to feed a plate to printing position at each cycle of operation of the machine, means to operate the plate feed and the platen, a clutch connection between said operating means and the platen, selector mechanism responsive to said indexes carried by the address plates to control the operation of said clutch, said selector mechanism including a normally open electric timing switch, a pair of selector switches, one of which is normally open and the other normally closed, an electrical connection between the timing switch and the selector switches, a solenoid operatively connected to said clutch, a manually operable switch connecting the solenoid with either one of said selector switches at the will of the operator, means operative on said timing switch to connect the selector switches with a source of electrical energy once in each cycle of operation of the machine, and means operative on the selector switches and responsive to the indexes to open the normally closed switch and close the normally open switch, whereby the clutch will be moved to one position under the influence of a certain index at one setting of the manual switch and will be moved to another position when under the influence of a similar index, but with another setting of the manual switch.

8. In a selective printing machine of the character described, the combination of means for feeding printing members one after another to printing position, some of said printing members having thereon selective indexes, an electric

switch to determine whether the machine prints from selected printing members or skips selected printing members.

9. In an address printing machine of the type arranged to print addresses from a series of address plates, a platen, feeding means to feed the plates one at a time to printing position, means to operate the plate feed and the platen, a clutch connection between said operating means and the platen, selector mechanism responsive to indexes carried by the address plates to control the operation of said clutch, said selector mechanism including a normally open electric timing switch, a pair of selector switches, one of which is normally open and the other normally closed, an electrical connection between the timing switch and the selector switches, a solenoid operatively connected to said clutch, a manually operable switch connecting the solenoid with either one of said selector switches at the will of the operator, means operative on said timing switch to connect the selector switches with a source of electrical energy once in each cycle of operation of the machine, and means operative on the reflector switches during the latter part of one cycle of operation, and responsive to the indexes to open the normally closed switch and close the normally open switch, and mechanical means operated by said solenoid and acting on the clutch at the next cycle of operation to move the clutch to one position under the influence of a predetermined index and one setting of the manual switch, and wherein said last-named means will operate to move the clutch to a different position under the influence of a similar index when the manual switch is moved to a different position.

WALTER T. GOLLWITZER.
